US00D906954S

(12) **United States Design Patent** (10) Patent No.: **US D906,954 S**
(45) Date of Patent: ** Jan. 5, 2021

(54) **BATTERY BOX**

(71) Applicant: **SHENZHEN IVPS TECHNOLOGY CO., LTD.**, Shenzhen (CN)

(72) Inventor: **Junwei Ouyang**, Shenzhen (CN)

(73) Assignee: **Shenzhen IVPS Technology Co. Ltd.**, Shenzhen (CN)

(**) Term: **15 Years**

(21) Appl. No.: **29/658,409**

(22) Filed: **Jul. 31, 2018**

(30) **Foreign Application Priority Data**

Apr. 23, 2018 (CN) 2018 3 0168626

(51) **LOC (13) Cl.** **13-02**

(52) **U.S. Cl.**

USPC **D13/103**; D27/101

CLAIM

The ornamental design for a battery box, as shown and described.

DESCRIPTION

FIG. 1 is a front perspective view of a battery box showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof, and;

FIG. 8 is a rear perspective view thereof.

The broken lines in the drawings are for the purpose of illustrating portions of the battery box that form no part of the claimed design.

1 Claim, 8 Drawing Sheets
